SHIFTING POST LOOSE LEAF BINDER

George Herbert Arnold Paget, West Vancouver,
British Columbia, Canada

Application August 13, 1956, Serial No. 603,490

4 Claims. (Cl. 129—12)

This invention relates to improvements in loose leaf binders.

An object of the present invention is the provision of a loose leaf binder which may be partially opened up to provide free access to the sheets thereof without danger of the sheets accidentally becoming displaced.

Another object is the provision of a binder with a locking arrangement for the sheets which may be released for the easy insertion of a sheet, and/or for the removal of a sheet without danger of shifting other sheets which may be in contact with the one being removed.

Another object is the provision of the combination of a binder of the nature described along with a sheet especially designed to co-operate with the locking arrangement of the binder.

A further object is the provision of a binder and sheet arrangement whereby the sheets may readily be inserted and removed without damaging the post-receiving slots thereof.

A binder according to the present invention includes a pair of covers having a locking arrangement at corresponding ends thereof. The locking arrangement includes a stationary and a movable post. These posts are usually mounted on the back cover of the binder, and they are so described herein, but they may also be mounted on the front cover. The stationary post is fixedly mounted on the back cover and fits through a hole in the other cover, while the movable post is mounted on the same cover spaced from the stationary post and projects through a hole in said other cover. One of the holes in the front cover is a slot, and this is usually the one through which the movable post projects. Suitable means is connected to the movable post for moving it towards and away from the stationary post, and means is provided on the front cover releasably connecting it to both posts.

This binder is used in combination with a sheet having spaced L-shaped slots extending inwardly from an edge thereof with base portions extending towards each other. The binder posts normally fit in the base portions of the sheet slots to lock the sheet in the binder. When the movable post is shifted away from the stationary post, the sheet may easily be inserted and withdrawn.

An example of this invention is illustrated in the accompanying drawings, in which,

Figure 1 is a perspective view of this binder with the covers locked in the normal position, and showing the locking arrangement thereof,

Figure 2 is a plan view, with parts broken away, of the front cover and locking arrangement at the end of the binder,

Figure 3 is a horizontal section taken on the line 3—3 of Figure 1,

Figure 4 is a plan view similar to Figure 2 of the back cover,

Figure 5 is an enlarged vertical section through both covers, taken on the line 5—5 of Figure 2,

Figure 6 is an enlarged vertical section taken through both covers on the line 6—6 of Figure 2,

2

Figure 7 is a vertical section taken through the top cover only on the line 7—7 of Figure 2, and

Figure 8 is a plan view of the slotted end of a sheet used in co-operation with this binder, the two binder posts being shown in their normal positions in the sheet slots.

Referring to the drawings, 10 is the shifting post loose leaf binder having a plurality of sheets 12 removably positioned therein. These sheets are especially designed for this binder, and each one has spaced L-shaped slots 15 and 16 extending inwardly from an edge 17 thereof. These slots have base portions 19 and 20 extending towards each other, as clearly shown in Figure 8. The base slots 19 and 20 form lips 21 and 22 at the inner side of their respective slots 15 and 16, and if desired these lips may be bevelled at 23 and 24 in order to widen the entrances of the slots at the sheet edge.

The binder 10 includes covers 30 and 32. As previously stated, either of these covers may be the front and the other the back cover, but for the sake of convenience, 30

20 will be considered the front cover and 32 the back cover. A locking arrangement generally designated by the numeral 35 is located at corresponding ends of the covers, as clearly shown in Figure 1. This locking arrangement includes a stationary post 38 and a movable post 40

25 permanently connected to one cover and releasably connected to the other.

In the preferred form of the invention, elongated substantially tubular casings 44 and 46 extend along corresponding ends of covers 30 and 32, and are connected thereto by hinges 48 and 49, respectively.

The stationary post 38 is fixedly secured to the casing 46 in any desired manner. In the illustrated example, the post is provided with a threaded projection 52 at its inner end which extends through the top of casing 46 and is threaded into a block 53 fixedly mounted within said casing, see Figures 3 and 5. This post projects outwardly from the casing and cover and extends through a hole 55 in casing 44 of cover 30.

Post 40 is fixedly mounted on a bar 58 slidably mounted in casing 46 near one end thereof, said post being spaced from post 38. The post may be connected to the bar in any convenient manner. This may be done by means of a threaded projection 60 which extends from the inner end of the post and is threaded through a block 61 secured to the bar, see Figures 4 and 6. The post extends through a slot 62 in the inner surface of casing 46, see Figure 4.

The bar 58 may be of any convenient shape, and it may be guided within casing 46 in any desired manner. Figures 3 and 6 illustrate a desirable type of bar. This bar is formed by bending a piece of suitable material, such as metal, back on itself to provide two overlapped thicknesses 63 and 64 with a tubular head 65 along one edge and oppositely projecting feet 66 and 67 along its opposite edge. The head and feet of this bar fit into the cross sectional shape of casing 46 to provide sliding connections therebetween, as clearly shown in Figure 6.

Post 40 extends from casing 46 through a hole 70 through casing 44 of cover 30. Either of the holes 55 or 70 should be a slot, and in this example, the latter is a slot, as shown in Figure 1.

A locking bar 75 is slidably mounted in casing 44, and it may be of any desired construction. However, it is preferably formed with the same cross sectional shape as the bar 58, and this is shown in Figures 5 to 7. The locking bar has slots 77 and 78 therein through which posts 38 and 40 extend.

The bars 58 and 75 may be shifted back and forth along their respective casings in any desired manner. In this example, bar 58 has a recess 82 formed therein near one end thereof, said recess having a restricted entrance 83. A screw 85 is threaded through a nut 86 fixedly

mounted in casing 46 near an end thereof, and has a head 87 on its inner end freely fitting into the bar recess 82. It is preferable to use a screw having a coarse thread so that it will be quick-acting, that is, one revolution of the screw will move the post through a relatively large portion of its required travel. The outer end of the screw projects beyond the casing and is squared as at 89 to receive a key or the like.

Another screw 92 projects into an end of casing 44 and is threaded through a nut 93 fixedly mounted therein. This screw has a head 95 on its inner end freely fitting in a recess 96 in locking bar 75, said recess having a restricted entrance 97 at the bar end. This screw preferably has a coarse thread, and projects beyond the end of the casing and is squared as at 99 to receive a key or the like.

The sheets 12 fit between the covers 30 and 32 of binder 10.

Posts 38 and 40 extend through the base portions 19 and 20 of slots 15 and 16 of the sheets, as shown in Figure 8. With this arrangement, the sheets cannot be withdrawn from the binder even if the covers are not tightly pressed against said sheets.

When entries are being made on the binder sheets, it is helpful to have the sheets fairly loose therein, but this cannot be done if there is a danger of the sheets being accidentally dislodged from the binder. Furthermore, the sheets lie flatter in the open binder when they are loose than when they are tightly gripped in the binder. One of the advantages of this binder is that the locking bar 75 may be moved by turning screw 92 to free the posts 38 and 40, after which cover 30 may be moved away from cover 32 to loosen the sheets, and then it may be locked on the posts by turning the screw further in the same direction to cause the bar to bind on the stationary post. The sheets are now fairly loose in the binder, as there is a minimum of contact between the sheets and posts due to the particular design of the slots in the sheets. By referring to Figure 8, it will be seen that the sheets come into contact with about 50% of each post only, as indicated at 102 and 103. Although the sheets are loose, they cannot come out since the posts are still in the base portions of the sheet slots, lips 21 and 22 preventing dislodgment of the sheets at this time.

When it is desired to remove a sheet from or insert one into the binder, the locking bar is shifted to its release position. Then screw 85 is turned to draw bar 58 along its casing to shift post 40 away from the stationary post 38. Post 40 moves to the position shown in dotted lines in Figure 8 at this time in line with the main portion of slot 16. Lips 21 still tend to keep the sheets on post 38. Therefore, the sheet to be removed must be pulled and more or less swung around the stationary post in order that it may be withdrawn from the binder. This swinging action tends to free it from the sheets that may be pressing against its opposite faces, and as the latter sheets are still held in the binder by their respective lips 21 at the stationary post, there is very little danger of them coming out with the sheet being removed. A sheet is inserted in the binder when it is in the unlocked state by first moving slot 15 over post 38, and then swinging the sheet around the post to cause post 40 to enter slot 16. Once this is done, screw 85 is turned to move post 40 back towards post 38. This causes relative movement between the sheet and posts so that the latter end up in the base portions of the slots, thereby positioning the sheet correctly in the binder. The operation is completed when bar 75 is shifted to grip the posts to lock the cover in place.

What I claim as my invention is:

1. In a loose leaf binder, the combination comprising a pair of covers, a stationary post mounted on one cover near an end thereof and projecting outwardly through a hole in the other cover, said hole being just large enough to accommodate the stationary post, a movable post

mounted on said one cover spaced along said end from the stationary post and extending through a hole in said other cover, the hole in said other cover being a slot, means connected to the movable post for moving it towards and away from the stationary post, a locking bar slidably mounted on said other cover and having slots extending longitudinally thereof in registry with the cover hole and slot and through which the posts extend, and means connected to the locking bar for shifting it along its cover in one direction to cause the bar to bind on the posts and in the opposite direction to free itself from the latter, said bar slots being so located and of such length that continued movement of the bar in said opposite direction causes the bar to bind on the stationary post and on the movable post when the latter is in a normal position at one end of the bar slot through which it extends to lock said cover on the posts while permitting the movable post to be moved towards the opposite end of its slot without releasing said other cover.

2. In a loose leaf binder, the combination comprising a pair of covers having tubular casings along corresponding ends thereof, a stationary post mounted on one casing and fitting through a hole through the other casing, said hole being just large enough to accommodate the stationary post, a bar slidably mounted in said one casing, a post mounted on the bar spaced from the stationary post and extending out through a slot in said one casing and through a slot in said other casing, means connected to the bar for moving it and the post mounted thereon along said one casing, a locking bar slidably mounted in said other casing and having slots extending longitudinally thereof in registry with the casing hole and slot and through which the posts extend, and means connected to the locking bar for shifting it along said one casing in one direction to cause said bar to bind on the posts and in the opposite direction to free itself from the latter, said bar slots being so located and of such length that continued movement of the bar in said opposite direction causes the bar to bind on the stationary post and on the movable post when the latter is in a normal position at one end of the slots through which it extends to lock said other casing on the posts while permitting the movable post to be moved towards the opposite end of its slot without releasing said other casing.
3. In a loose leaf binder, the combination of a sheet having spaced L-shaped slots extending inwardly from an edge thereof with base portions extending parallel to said edge in opposite directions, and a pair of covers having a locking arrangement at corresponding ends thereof; said locking arrangement comprising a stationary post mounted on and projecting outwardly from one cover, a post movably mounted on said one cover spaced from and substantially parallel with the stationary post, the other cover having therethrough a hole just large enough to accommodate the stationary post and a slot spaced therefrom and aligned therewith through which the movable post slidably extends, means at said one cover and connected to the movable post for moving it towards and away from the stationary post and along the slot of said other cover, a locking bar slidably mounted on said other cover and having slots extending longitudinally thereof in registry with the cover hole and slot and through which the posts extend, and means connected to the locking bar for shifting it along its cover in one direction to cause the bar to bind on the posts and in the opposite direction to free itself from the latter, said bar slots being so located and of such length that continued movement of the bar in said opposite direction causes the bar to bind on the stationary post and on the movable post when the latter is in a normal position at one end of the slots through which it extends to lock said other cover on the posts while permitting the movable post to be moved towards the opposite end of its slots without releasing said other cover; said posts normally fitting in the base por-

tions of the sheet slots to lock the sheet in the binder and when the movable post is shifted away from the stationary post, the sheet may be withdrawn.

4. In a loose leaf binder, the combination of a sheet having spaced L-shaped slots extending inwardly from an edge thereof with base portions extending parallel to said edge in opposite directions, and a pair of covers having tubular casings along corresponding ends thereof with a locking arrangement associated therewith; said locking arrangement comprising a stationary post mounted on and projecting outwardly from one casing, a bar slidably mounted in said one casing, a post mounted on the bar spaced from and substantially parallel with the stationary post and extending out through a slot in said one casing, the other casing having therethrough a hole just large enough to accommodate the stationary post and a slot directly over and aligned with said one casing slot and through which the bar post slidably extends, means at said one casing and connected to the bar for moving it and the post mounted thereon along the casings and the aligned slots thereof, a locking bar slidably mounted in said other casing and having slots extending longitudinally thereof in registry with the casing hole and slot through which the posts extend, and means con-

nected to the locking bar for shifting it along its casing in one direction to cause said bar to bind on the posts and in the opposite direction to free itself from the latter, said bar slots being so located and of such length that continued movement of the bar in said opposite direction causes the bar to bind on the stationary post and on the movable post when the latter is in a normal position at one end of the slots through which it extends to lock said other casing on the posts while permitting the movable post to be moved towards the opposite end of its slots without releasing said other casing; said posts normally fitting in the base portions of the sheet slots to lock the sheet in the binder and when the movable post is shifted away from the stationary post the sheet may be withdrawn.
